UNITED STATES PATENT OFFICE.

ABEL HENNING, OF ANN ARBOR, MICHIGAN, ASSIGNOR OF TWO-THIRDS TO
HENRY W. DOUGLAS, OF ANN ARBOR, MICHIGAN.

VALVE-GRINDING MECHANISM.

SPECIFICATION forming part of Letters Patent No. 693,967, dated February 25, 1902.

Application filed October 31, 1901. Serial No. 80,713. (No model.)

To all whom it may concern:

Be it known that I, ABEL HENNING, a citizen of the United States, residing at the city of Ann Arbor, in the county of Washtenaw and State of Michigan, have invented certain new and useful Improvements in Valve-Grinding Mechanism, of which the following is a specification.

This invention relates to a new and improved device for grinding the valves on gas-meters, although the structure is very well adapted for similar operations in other structures.

The valves in gas-meters become corroded or from their operation become slightly displaced and do not seat properly, so that it is necessary at intervals to grind the valves, so that they seat and cause the proper operation of the meter. This has heretofore been done by workmen placing the end of a file on a grinding-plate which is provided with a sheet of emery on one side and moving the same with a slight rotary motion on a valve-seat. This requires considerable skill on the part of the workmen and is very slow in its operation and but one valve-seat can be ground at a time.

The objects of the invention are, first, to provide a suitable machine for accomplishing this purpose without dissembling the meter further than to remove the valve-lids; second, to provide an improved structure whereby a proper rotary motion under pressure will be imparted to a valve-grinding plate to accomplish the desired result, and, third, to provide a structure which is readily attached and detached to a meter whereby its operation is facilitated.

Further objects will definitely appear from the detailed description to follow.

I accomplish the objects of my invention by the devices and means described in this specification.

The invention is clearly defined and pointed out in the claims.

A structure embodying the features of my invention is fully illustrated in the accompanying drawings, forming a part of this specification, in which—

Figure 1 is a detail side elevation view of my improved valve-grinder in position on a

gas-meter, portions of the meter being broken away to show details and the coupling for the machine being shown in section. Fig. 2 is an enlarged detail sectional view on line 2 2 of 55 Figs. 1 and 3, showing details of the adjusting-clamps and frame. Fig. 3 is a detail front elevation view of the structure appearing in Fig. 1, the meter being shown in section on a line corresponding to line 3 3 of 60 Fig. 1, one of the spring-pressure devices being shown in section to show details of its construction. Fig. 4 is a detail sectional plan view taken on a line corresponding to line 4 4 of Fig. 3, showing the position and operation of the valve-grinding plates. Fig. 5 is a detail sectional plan view on line 5 5 of Fig. 3, showing details of the valve-grinding plates and their connections, the position of the valve-seats being indicated by dotted lines 70 beneath. Fig. 6 is a detail sectional view taken on a line corresponding to line 6 6 of Fig. 5.

In the drawings all of the sectional views are taken looking in the direction of the little arrows at the ends of the section-lines, and similar letters of reference refer to similar parts throughout the several views.

Referring to the lettered parts of the drawings, A is a meter, and A' A' are the upwardly-projecting casings, on the upper ends of which are formed the valve-seats, as clearly appears in Figs. 1 and 3.

A" is the gas-pipe at the side of the meter, which is utilized as the base for the support 85 of my improved grinding-machine. A pin C is secured to the top thereof by a suitable union C' and projects upward and is embraced by the clamp B', which is adjustable up and down thereon and which carries the main frame B of the machine. The horizontal bracket B" extends from this main frame, and in this is journaled a vertical shaft E, which is slightly offset at the bottom to form a crank and has a gear F', which is actuated from a beveled gear F, supported on a suitable loop extending up from the frame B, and this is actuated by a crank D' on the shaft D. Pins G' G' are secured by the adjustable arms G to the bracket B" and are held adjustably in 95 position by the screw-nuts a a, so that the pins G' can be moved into proper relation to

the valve-seats no matter what design of meter it is intended to work upon. Arms H H, suitably slotted, are secured to the upper side of the bracket B" by suitable set-screws e e 5 and are adapted to be adjusted so that their outer ends extend over the central part of the valve-seat below as near as possible, the same being made adjustable, so that the machine can be readily adjusted to different kinds of 10 meters. Plates J J are provided with a layer of emery cloth or paper r on their under sides and have arms J' J' extending therefrom and journaled on the lower end of the crank-shaft E. The arms J' are provided with longitudinal slots, which embrace the lower end of the pins G' G'. A pivot-seat i is in the central part of the top of each of these grinding- 15 plates, and a similar pivot-seat is on the under side of the outer ends of the arms H. A pressure device consisting of a tube I, with a 20 conical bearing at the top, and a pin I', with a conical pivot at the bottom telescoping within the same, is provided for insertion between the arm H and the grinding-plate J, tension 25 being kept on these devices by a coiled spring n within the tube I.

I have thus enumerated and described all of the parts of my improved grinding-machine and will now explain fully its operation. 30 The meter is of course disconnected, and the pin C is secured to the gas-pipe thereof, and the bracket B' is secured to this pin at a suitable height. The valve-lids are removed, and the grinding-plates J are brought to the desired 35 position and the different parts adjusted to properly align with the valve-seats. The spring-pressure device I I' is then inserted and will bear directly over the valve-seat against the plate J and afford a constant but 40 yielding pressure. On turning the crank D' the shaft E will be rotated, and owing to the lower end being formed like a crank of very short throw the arms J' J' will be caused to oscillate on the pins G' G' and will be moved 45 back and forth thereon, the slots in the arms J' permitting such movement. This action therefore will give each of the plates J a slight rotary motion, owing to the action of the crank E on the arms J' J', and in a very 50 short time the valve-seats will be ground, when the machine can be quickly disconnected by unscrewing the union C'. As the machine will now have been adjusted to the particular style of meter in use, it can be quickly 55 transferred to another and the valve-seats be ground at a very rapid rate. Thus it is possible to accomplish in a very short time the proper grinding of the valve-seats of a large number of meters, which has heretofore required 60 the employment of a skilled mechanic and the operation being very laborious, requiring several hours to accomplish what by this simple and practical device can be accomplished in a few minutes.

65 I have shown the structure in the form which I consider best adapted and most prac-

tical for the use intended. However, I am aware that other devices might be made use of for securing a machine of this kind in position, and I desire to remark that for a given 70 style of meter of course it would be necessary to make different parts adjustable, as they could be made so that the different pivot-centers would have the right relation for the particular meter intended to be operated 75

I have shown what I consider the most practical spring-pressure device, but desire to remark in this connection that a spring-pressure device for applying pressure could be 80 readily produced of different design, and while I desire to claim the particular spring-pressure device in this relation I also wish it to be understood that I claim such spring-pressure device broadly. The particular form 85 for the supporting-framework and the driving means are of course capable of very great variation, though, as I have before remarked, I consider that I have produced the structure in its most practical and simple form. 90

Having thus described my invention, what I claim as new, and desire to secure by Letters Patent, is—

1. In a valve-grinder for gas-meters, the combination of a pin C with a coupling for 95 uniting it with a gas-pipe on a meter; a frame B with adjusting-clamp B' for embracing the said pin C; a horizontal bracket B"; a pair of depending pins G' secured to the under side of the bracket, B" by the adjustable bases G; 100 adjustable arms H secured to the top of said bracket B", having suitable pivot-seats on their under side; a vertical crank-shaft E in the said bracket B" and driving-gears F, F', operated by the crank and shaft D', D; grinding-plates J, J, with pivot-seats on the top thereof; adjustable slotted arms J', J', extending from said grinding-plates, the slots of 105 which embrace the downwardly-depending pins G', G', and the outer ends of which arms 110 are secured to the crank-shaft E; spring-pressure devices provided with conical pivots at the top and bottom consisting of the tube I and the pin I' telescoping within the same; and a spring n for holding the same normally 115 under tension, placed between the pivot-seats on the arm H and the pivot-seats on the top of the grinding-plate J, all coacting substantially as described for the purpose specified. 120

2. In a valve-seat-grinding device, the combination of a frame B with means for securing the same to the gas-meter; a horizontal bracket B"; a pair of depending pins G' secured to the under side of the bracket B", by the adjustable bases G; adjustable arms H 125 secured to the top of said bracket B", having suitable pivot-seats on their under side; a vertical crank-shaft E in the said bracket B" and driving-gears F, F', operated by the crank and shaft D', D; grinding-plates J, J, with 130 pivot-seats on the top thereof; adjustable slotted arms J', J', extending from said grind-

ing-plates, the slots of which embrace the downwardly-depend ing pins G', G' and the outer ends of which arms are secured to the crank-shaft E; spring-pressure devices provided with conical pivots at the top and bottom consisting of the tube I and the pin I' telescoping within the same; and a spring n for holding the same normally under tension, placed between the pivot-seats on the arm H and the pivot-seats on the top of the grinding-plate J, all coacting substantially as described for the purpose specified.

3. In a valve-seat-grinding device, the combination of the frame B with means for securing the same to the gas-meter; a horizontal bracket secured to the said frame; a downwardly-extending pin secured to the under side thereof; a vertical crank-shaft supported by the said bracket with gears F, F' for actuating the same; a grinding-plate with pivot-seat at the top and a projecting slotted arm, the slot of which embraces the said downwardly-projecting pin, the outer end of which is secured to the said crank-shaft; a spring-pressure device provided with a conical pivot at the top and bottom consisting of the tube I and pin I' telescoped within the same and

forced normally outward by the coiled spring n within, all coacting for the purpose specified.

4. In a valve-grinding machine, the combination of a main frame; a downwardly-projecting crank-shaft therefrom; a pin extending down in proximity to said crank-shaft; a plate with a slotted arm to embrace the said pin and be actuated by the said crank-shaft; and a spring-pressure device for insertion between the said grinding-plate and a fixed part of the frame; and suitable means for actuating the crank-shaft, all coacting for the purpose specified.

5. In a valve-grinding machine, the combination of a suitable stationary frame; a grinding-plate; a spring-pressure device for insertion between the grinding-plate and the frame; and means of oscillating or rotating the grinding-plate, as specified.

In witness whereof I have hereunto set my hand and seal in the presence of two witnesses.
